PACKAGING MACHINE

George I. Hohl, Brooklyn, N. Y., and Harry L. Evans, Newport, R. I., assignors to Cartoning Machinery Corporation, Newport, R. I., a corporation of New Jersey

Application June 12, 1936, Serial No. 84,860

23 Claims. (Cl. 226—14)

This invention relates, generally, to automatic packaging machinery, and the invention has reference to improvements in machines for assembling and inserting articles into receptacles, such as paper cartons or the like, and more particularly, to a novel automatic machine for collecting and assembling a desired number of superimposable flat articles, such e. g. as enveloped razor blades, and thereupon inserting and enclosing the same within a box, carton or like receptacle or enclosure.

Automatic packaging machines of the kind to which the present invention relates, ordinarily comprise mechanism for successively delivering and expanding collapsed cartons, means to collect, assemble and insert the articles into the cartons, and means to close the cartons. The present invention deals with those portions of such machinery which perform the operations of collecting and assembling the articles from a source of supply thereof, and thereupon inserting assemblies comprising a given number of said articles into the cartons; and, as a consequence of this, illustration and description of the means for delivering, expanding and closing the cartons, with the exception of the carton conveyer per se, have been omitted from the accompanying drawings and from this specification.

This invention has for its principal object to provide, in combination, a novel construction and arrangement of cooperative means for collecting the articles to be packaged, arranging the same in assemblies each containing a given number thereof in superimposed relation, and thereupon inserting these assemblies into the cartons or receptacles within which the same are to be enclosed.

The invention has for another object to provide a plurality of pneumatic pick-up drums and a corresponding plurality of magazines to supply the articles to said drums, together with novel means for controlling the movement of the articles from the magazines to the drums.

The invention has for another object to provide in combination with the pick-up drums an article collecting and assembling conveyer running transversely across the drums so as to receive the articles from the latter, and, by the combined operation of the drums and conveyer, arrange said articles within the conveyer pockets in assemblies containing a given number thereof; novel means being provided for stripping the articles from the drums and for inserting the stripped articles into the conveyer pockets.

Other objects of this invention are to provide

novel means cooperative with the pick-up drums for detecting a faulty article or the omission of an article from its proper place upon a drum, and to further provide means cooperative with the article collecting and assembling conveyer for detecting an assembly of articles faulty in condition or defective in number.

Other objects of this invention, not at this time more particularly enumerated, will be understood from the following detailed description of the same.

An illustrative embodiment of the present invention is shown in the accompanying drawings, in which:—

Fig. 1 is a partial end elevation of those portions of the packaging machine which involve the novel features of construction, arrangement and mode of operation involved in the present invention; Fig. 2 is a transverse vertical section, taken on line 2—2 in Fig. 1; Fig. 3 is a fragmentary vertical sectional view, on an enlarged scale, showing the cooperative relation of a magazine and a corresponding pick-up drum, with the means for controlling the movement of an enveloped blade from the former to the latter as disposed in normal initial position and with the magazine lowered non-feeding position; Fig. 4 is a similar view, showing the operation of the blade feeding or control means; Fig. 5 is also a similar view, showing further operation of certain elements of the blade feeding or control means; Fig. 6 is also a similar view, showing the magazine in elevated blade discharging position; and Fig. 7 is a fragmentary horizontal section, taken on line 7—7 in Fig. 3. Fig. 8 is a detail vertical section, taken on line 8—8 in Fig. 2, the same showing the pneumatic control valve and suction means of a pick-up drum, said view being drawn on a somewhat enlarged scale. Fig. 9 is a fragmentary vertical sectional view, on an enlarged scale, showing a blade transfer or stripping means cooperative with a pick-up drum and also showing the means for delivering a stripped blade to the collecting and assembling conveyers; Fig. 10 is a top plan view of the operative free end portion of a blade transfer or stripping means; and Fig. 11 is a fragmentary detail view of the cam for actuating the primary detector mechanism of the machine.

Similar characters of reference are employed in the above described views, to indicate corresponding parts.

Referring to the drawings, the reference character 1 indicates a platform or bed plate which is a part of the frame-work or supporting structure of the machine. Upstanding from said plat-

form or bed plate are a pair of longitudinally spaced apart standards 2. Journalled in and extending between said standards 2, at the upper rearward portions thereof, is a suitably actuated longitudinal drive shaft 3; and also journalled in and extending between said standards 2, forwardly of and parallel to said drive shaft 3 is a cam shaft 4, driven by gearing 3'-4' from drive shaft 3. Journalled in and extending between 5 said standards 2, at the upper forward portions thereof, is a pick-up drum shaft 5. Fixed on said shaft 5, so as to be revolved thereby, are a plurality of longitudinally spaced apart pick-up drums 6. Any suitable number of such pick-up drums 10 may be employed, but preferably there are five of the same, as shown in Fig. 2. Shaft 5 is continuously driven, so as to revolve said pick-up drums, by means of suitable transmission means which is preferably actuated by and from drive 15 shaft 3 through cam shaft 4 which is geared thereto. Illustrative of one means for so actuating said shaft 5 and pick-up drums 6 is a chain and sprocket transmission 7 running between cam shaft 4 and said shaft 5, as shown in Figs. 20 1 and 2.

Each pick-up drum is provided at circumferentially spaced points along its perimeter with somewhat projecting concave suction cups 8, which are made of suitable resilient material such 25 as rubber; each such cup having an axial stem or butt 9 countersunk into the pick-up drum body, said stem or butt having an axial bore 10 extending outwardly therethrough into communication with the interior of the cup at the bottom 30 of its concave face. Extending radially inward from each suction cup and in communication with the stem bore 10 thereof is a passage or duct 11, which terminates at its inner end in a port 12 opening outwardly through the hub face 35 of the pick-up drum. Mounted on shaft 5 in cooperative relation to the hub portion of each pick-up drum and at the side thereof in which said ports 12 are disposed in an annular row, is a pneumatic control valve body 13. Said valve 40 bodies 13 are held stationary, i. e. against rotation with said shaft 5, so that corresponding pick-up drums will revolve relative thereto. Any suitable means for holding the valve bodies 13 thus 45 stationary may be provided, as e. g. by the anchor-arms 14 extending therefrom and secured to tie-bars 15 suitably affixed to a stationary part of the machine frame-work. Each valve body 13 in its pick-up drum abutting face with an arcuate suction channel or duct 16 and with an arcuate 50 suction relief channel or duct 17, into and out of communication with which pass said ports 12 of the pick-up drum suction passages or ducts 11 as said drum revolves. Each valve body 13 is also provided with an extension 18 having a passage 19 communicating with its suction channel or duct 16, and suitably coupled with said passage 19 is a flexible hose or conduit 20 which communicates with a suitable exhaust pump means (not shown). Formed in the perimeter of each pick-up 55 drum adjacent to the trailing side of each suction cup 8 thereof is an indented or notch-like space 21, the purposes of which will subsequently be set forth. In the arrangement of the pick-up drums, as shown, each drum is provided with six suction cup means spaced about its perimeter at sixty degree intervals; it will be understood however that such number is subject to variation, and that more or less than six said suction cup means may be provided, if desired.

Secured to and extending upwardly from said

standards 2 are rearwardly inclined bracket bars 22. Journalled in and extending between the upper free end portions of said bracket bars 22 is a magazine fulcrum shaft 23 for pivotally mounting, subject to controlled vertical oscillations, a plurality of magazines 24. These magazines 24 are of upwardly open trough or chute-like form, and correspond in number to the number of pick-up drums with which they respectively cooperate. The magazines 24 incline downwardly at an approximate angle of thirty degrees from a horizontal plane, and their free lower end portions terminate adjacent to the pick-up drums. Supported by and between said standards 2, intermediate the pick-up drums 6 and the free end 15 portions of said magazines 24, is a bridge bar 25. The magazine facing side of said bridge bar 25 is provided, for cooperation with each magazine, with a group of vertically extending guide channels (see Fig. 7), comprising a central guide channel 26 and side guide channels 27, at the lower ends of which are magazine stop ledges 28. Each magazine is provided with corresponding groups of projections or tongues at its free end to enter and ride in said channels, the same comprising 25 a central projection or tongue 29 projecting from the magazine bottom, and projections or tongues 30 extending from the magazine sides. The stop ledges 28, when engaged by said projections or tongues 29—30, limit the downward movement of 30 the magazines, whereby the latter are disposed in a non-feeding position.

Illustrative of the use and operation of the machine of this invention, the articles to be packaged are shown to comprise envelopes in each of which is enclosed a safety razor blade. For convenience of description, the thus enveloped safety razor blades will be hereinafter generally referred to as "blades", which expression will be understood to mean units each consisting of a 40 safety razor blade as enclosed within a protecting envelope, which is the common method of handling the blades for commercial distribution.

A quantity of blades 31 are stacked within each magazine in upstanding position within the 45 trough or chute-like interior thereof, and when the magazines are in lowered non-feeding position, the lower ends of the columns or stacks of blades will abut the rearward face of said bridge bar 25, which thus sustains the weight thereof. 50 To prevent outward displacement of the blades 31 from the magazines, each magazine is provided with an overhanging guard or top plate 32, which is supported from the magazine body by means of a carrying bracket 33, or in any other 55 suitable manner.

Means is provided for periodically lifting or swinging upward the magazines 24 to blade feeding position, whereby a segregated small quantity of blades 31 are delivered onto the top of the 60 bridge bar 25, and thus in position to be successively transferred to the pick-up drum 6 so as to be gripped by the suction cups 8 of the latter. The means for oscillating the magazines to such end comprises lift levers 34 pivotally mounted at the inner sides of the standards 2 for rearward extension beneath the magazines. The magazines are provided intermediate their ends and at their under sides with bearing knuckles 35 through which extends a cross-head shaft 36. 70 Links 37 interconnect the ends of said cross-head shaft 36 respectively with the free ends of the respective lift-levers 34. Mounted on said cam shaft 4, so as to be actuated thereby, are magazine oscillating cams 38, prefer-

ably one adjacent to each lift lever 34. Each cam 38 is provided with a suitably shaped cam race 39, in which rides the roller stud 40 of the corresponding lift lever 34. The cams 38 are so arranged as to properly time the rise and fall movements of the magazines relative to the revolution of the suction cups 8 carried by the pick-up drums.

Means are provided for retaining the segregated groups of blades 31 supported away from the path of movement of the pick-up drum suction cups 8, said means being operative to transfer the groups toward the pick-up drums when a suction cup 8 is properly aligned or opposed thereto ready to receive a blade to be gripped thereby. This means comprises a rock-shaft 41 which is journaled in and which extends between said standards 2 beneath said cam shaft 4. Fixed on said rock-shaft 41, in such arrangement that a pair thereof are disposed in straddling relation to each pick-up drum for extension upwardly across the outer face of the bridge bar 25, are detent levers 42. The upper end portions of said detent levers 42 engage and support the segregated group of blades 31 delivered onto the bridge bar 25, and projecting rearwardly from said detent levers 42, into slots or openings 43 provided in the front face of said bridge bar for the reception thereof, are blade supporting lugs 44 which are substantially flush with the upper surface of said bridge bar. The means for effecting timed operation of said detent levers, comprises a lever arm 45 and a cam 46 mounted on said cam shaft 4. Said cam 46 is provided with a cam race 47 in which rides a roller stud 48 carried by said lever arm 45. Said cam 46 is so arranged as to produce a properly timed oscillation of said detent levers 42 relative to the revolution of the suction cups 8 carried by said pick-up drums. Mounted on the upper side of said bridge bar 25, in alignment with the sides of the magazines 24, are side plates 49, which serve to retain the blades 31 against lateral displacement when deposited and supported upon the bridge bar 25.

In the operation of the machine, the pick-up drums revolve in anti-clockwise direction. Prior to the arrival of a suction cup 8 in a position opposed to the segregated group of blades 31 supported on the bridge bar 25, the detent levers 42 occupy their initial inwardly swung position, whereby the same press back said group of blades so as to hold the outermost blade well clear of the moving pick-up drum and the approaching suction cup 8 (see Fig. 3). When the approaching suction cup 8 passes above the bridge bar 25 and in opposition to the blades 31 supported thereon, said detent levers 42 are moved outwardly, i. e. toward the pick-up drum, whereby the outermost blade is carried into contact with said suction cup 8 (see Fig. 4). As said suction cup arrives in position to receive a blade, the port 12 of the passage 11 serving the same is brought into communication with the suction channel or duct 16 of the pneumatic control valve body 13, where-by the suction effect due to the connection of said channel or duct 16 with an exhaust pump means (not shown) is exerted by said suction cup 8 upon said blade thus carried into contact therewith, so that the continuous revolving movement of the pick-up drum operating to move onward the blade contacted suction cup 8, causes the latter to slide upwardly and away from the segregated group of blades said engaged outermost blade.

In order to prevent any of the group of segre-

gated blades except the suction cup contacted outermost blade from accompanying the movement of the latter, means is provided for engaging the top of the group of segregated blades so that the outermost blade may be stripped therefrom, said means being movable to engage the face of the outermost blade as it is pulled away in such manner as to prevent any tipping or tilting thereof which might tend to separate or release it from the grip of said suction cup. This means comprises a bar 50 to extend across the upper rear sides of said pick-up drums 6 and above the groups of segregated blades, said bar 50 being mounted for oscillation toward and from said pick-up drums by links 51 pivotally connected with the standards 2. The means for causing properly timed oscillatory movements of said bar 50, comprises a lever arm 52 pivotally mounted on said rock-shaft 41 as a fulcrum. Said lever arm 52 is provided with a roller stud 53 which is operatively engaged by a lever arm actuating cam 54 driven by cam shaft 4. Spring means 55 connected with said lever arm 52 yieldably holds the latter and its roller stud 53 in operative engagement with said cam 54. Said bar 50 is provided with a knuckle 56 whereby the same is operatively connected through link 57 with the free end portion of said lever arm 52. Carried by said bar 50 in cooperative relation with each pick-up drum and the corresponding blade magazine mechanism, are dependent stripper pieces 58 having laterally spaced forwardly projecting nosings 59 and 60, the right hand nosing 59 preferably projecting slightly beyond the left hand nosing, so that, when the stripper pieces 58 are retracted to normal initial position, and the group of segregated blades are outwardly moved by the detent levers 42 in position to engage the outermost blade, the tops of all the blades of said group, except the outermost blade, will underlie said stripper pieces and at least said nosing 59, so that as the outermost blade is gripped by a suction cup and started upwardly and away by revolving motion of the pick-up drum, all the remaining blades of the group will be restrained from any tendency to following movement (see Fig. 4). As the suction cup gripped blade continues to slide away from the segregated group of blades, said bar 50 and the stripper pieces 58 carried thereby are swung outwardly or toward the pick-up drum, thus pressing the stripper pieces 58 against the gripped blade, so as to hold the same firmly against the suction cup 8, and in resistance to the pressure of the remaining blades of the group which otherwise might tend to so tip or tilt the gripped blade as to risk possible accidental release thereof from the suction effect of the engaging cup (see Fig. 5). Such holding effect of the stripper pieces continues until the gripped blade is separated free and clear from the segregated group of blades, whereupon said stripper-pieces are returned to normal initial positions by the operation of the actuating means therefor.

Between the time that a blade has been gripped and removed by one suction cup of each pick-up drum, and while succeeding suction cups of the latter are moving to positions for the reception of blades, the magazine elevating means is timed to raise the magazines into registration with the top of said bridge bar 25, so that the columns of blades carried by the magazines are brought into aligned registration with the deposited segregated groups of blades supported by said bridge bar. By

this operation the blades in the magazines will gravitate toward said segregated blade groups so that blades will be replaced in said groups to compensate for the blades carried away by the pick-up drums (see Fig. 6). After this operation is effected, the magazines are again depressed to lowered normal initial positions. It will be obvious, that by reason of this operation of the blade magazines, the weight of the columns of blades therein is removed from the segregated groups of blades from which the pick-up drums collect and carry away the blades, and consequently risk of displacing the engaged blades of a considerable weight of blades is avoided. Owing to the dovetailed relation of the magazines to the bridge bar 25, separation of the columns of blades in the magazines from the segregated groups of blades deposited on the bridge bar, upon movements of the magazines relative to the latter, is assured, and occurs without risk of jamming or disturbing the operative relation of said blades to either the bridge bar or magazine.

As the pick-up drums 6 revolve, the blades picked up by the suction cups 8, as the latter pass the described blade magazines and blade feeding mechanisms, are carried around by the drums, and the gripping suction effect of the cups 8 is maintained since the ports 12 and passages 11 serving the latter continue to travel in communication with the arcuate suction channel or duct 16 of the pneumatic control valve (see Fig. 8). As the gripped blades are carried outwardly and downwardly, the same are caused to travel beneath and subject to the operation of a detector or tester mechanism, which by engaging the same test the same to determine the assured pressure of a blade within each enveloping wrapper by which it is enclosed. If a blade is present within the wrapper, it is allowed to pass on, but in the event an empty wrapper is presented beneath the detector or testing mechanism, the latter will be actuated to close an electrical circuit, which will energize suitable means (not shown) whereby the machine is brought to a stop and cannot be started again until an attendant replaces the detected empty wrapper with one properly containing a blade.

This detector or testing means comprises the following mechanism:—

Suitably affixed to the forward upper end portions of the standards 2 are upstanding bearing posts 61. Journaled in and between the upper ends of said bearing posts 61 is an oscillatable shaft 62, thus disposed to extend across and above said pick-up drums 6. Affixed to said shaft 62 is an actuating lever arm 63. Fixed on the cam shaft 4 is a detector means actuating cam 64 having a race 65 which is engaged by a roller stud 66 on the forked end 67 of a connecting rod 68, the outer end of the latter being pivotally joined to said lever arm 63 (see Figs. 1 and 11). Loosely pivoted on said shaft 62 to overhang the pick-up drums is a depressor frame, comprising side arms 69 between which extends a depressor bar 70. One of said side arms 69 is provided with a rearwardly extending tail-piece 71 to which is connected one end of a pull spring 72, the opposite end of which is anchored to an anchor lug 73 affixed to one of said bearing posts 61. Loosely mounted on said shaft 62 as a fulcrum, by means of fulcrum blocks 74 are a plurality of detector arms 75, the same being aligned above and corresponding in number to the number of pick-up drums 6. The forwardly extending portions of these detector arms 75 are

disposed above said depressor frame and across the depressor bar 70 thereto; the same are provided with adjustably mounted push-pins 76 adapted at proper times to engage and depress said depressor bar 70. Affixed to said shaft 62 outwardly of each side of the group of detector arms 75 are rearwardly extending lever arms 77 to and between the free ends of which is affixed a cross bar 78 which extends beneath and across the rearwardly extending portions of said detector arms 75. Extending loosely through the rearward end portion of each detector arm 75 is a stud 79 having a head 80 at its upper end to engage said detector arm, and having its lower end affixed to said cross-bar 78. A compression spring 81 is mounted around each stud 79 between the cross-bar 78 and the rearward ends of the detector arms, thus establishing yieldable connections between these parts. The free ends of the forwardly extending portions of said detector arms 75 are provided with depending feeler fingers 82 adjustably mounted in connection therewith. These feeler fingers 82 project toward the perimeters of the respective pick-up drums 6. One of the bearing posts 61 is provided with a forwardly and downwardly projecting bracket arm 83. Affixed to said bracket arm 83 so as to be rigidly supported thereby is an electrical switch box 84 having an upwardly presented exteriorly projecting push button 85 for actuating the switch contained therein. One of the side arms 69 of the depressor frame is provided with an extension 86 which is disposed above and across said switch box 84. Carried by said extension 86 is an adjustably mounted push pin 87 which is aligned with said switch push button 85, so that upon depression of said depressor frame said push pin 87 will be carried into operative actuating engagement with said switch push button 85. Means is provided for retaining said depressor frame in switch closing position once it has been moved thereto. This means comprises a spring actuated latch element 88 which is pivotally mounted upon a lateral extension of said bracket arm 83. At its upper free end, said latch element 88 is provided with a latch nosing 89, which normally presses against the side of said side arm extension 86 adjacent to the latter's free end. When said extension 86 is swung downward by depression of said depressor frame, said latch nosing 89 will swing over the upper side of said extension 86, thus locking down the depressor frame in switch actuating position until the latch element is manually released. In the operation of the machine, the above-described detector or testing mechanism functions as follows: As the suction cup gripped blades 31 are carried beneath the feeler fingers 82, and so disposed relative thereto as to expose to the touch of said feeler fingers those portions of the blade envelopes or wrappers which overhang the indented or notch-like spaces 21 provided in the pick-up drum peripheries, the actuating cam 64 operates to oscillate shaft 62 in anti-clockwise direction. Such movement of the shaft 62 swings upwardly the lever arms 77 and cross-bar 78 carried thereby, and thereby transmits through the compression springs 81 a downward swinging movement to the forwardly extending portions of said detector arms 75. Such movement of said detector arms 75 carries the feeler fingers 82 into engagement with the underlying blades. If such underlying blades comprise envelopes or wrappers having their proper blade content, the 75

blades will bridge across the indented or notch-like spaces 21, and the relatively unyielding blades will resist such downward movement of the feeler fingers 82, and consequently the detector arm movements will be arrested, and the further upward movement of cross-bar 78 will be absorbed by the compression springs 81. In such case, the movements of the detector arms are arrested before any depressing effect there-
 10 of upon the depressor frame is produced sufficient in amplitude to carry the push-pin 87 into actuating contact with the switch push button 87. If, however, any one of the blade envelopes or wrappers is empty, the downward movement of the feeler finger 82 engaging the same will not be opposed or resisted, since such empty wrapper or envelope will collapse under the pressure so that the feeler finger may force the same downwardly into the underlying indented space 21.
 15 The additional downward swinging movement of the detector arm 75, consequent upon this condition, is sufficient to cause its push-pin 76 to engage and thrust downwardly the depressor bar 70, whereby the extension 86 of one of the de-
 20 pressor frame side arms 69 is swung downwardly, against the tension of its normally uplifting pull spring 72, far enough to carry the push-pin 87 into actuating engagement with the switch push button 85, thereby closing the switch, and
 25 through the means actuated by the switch controlled circuit, causing the operation of the machine to be immediately stopped. As said extension 86 of the depressor frame swings down to switch actuating position, its upper margin 30 passes beneath the nosing 89 of latch element 88, whereupon the spring tension exerted upon the latter swings the same so as to engage said nosing over the extension 86, thus holding the depressor frame against return to normal initial
 35 position and thereby locking the same in switch closing position. By reason of this the machine attendant must manually release said latch element before the machine can be restarted, and consequently his attention will be called to the
 40 necessity for replacing the detected empty blade envelope or wrapper with one properly containing a blade, which, of course, he will proceed to do before restarting the machine. By this means the proper assembling of desired numbers
 45 of blades for insertion into an enclosing box or carton is assured. It will be understood that the above described operations periodically recur as each suction cup gripped blade passes the detector mechanism.
 50 Suitably mounted to run transversely across and beneath the pick-up drums 6 is a blade collecting and assembling conveyer means. This means comprises spaced supporting sprockets 90, the axle shafts 91 of which are journaled in suitable bearing members 92 supported upon the platform or bed-plate 1. Running over and between said sprockets 90 is an endless chain 93. Affixed to said chains, at interval spacing corresponding to the spacing of said pick-up drums 6, are trans-
 55 verse trough-like blade receivers or upwardly and endwise open pockets 94. Said conveyer means is so driven as to operate with intermittent motion, whereby a period of dwell of the receivers or pockets 94 in alignment with and beneath the pick-up drums occurs during which blades advanced by the pick-up drums 6 may be detached therefrom and delivered into the receivers or pockets 94. Any suitable means (not shown) may be employed for so actuating the blade collecting and assembling conveyer, such e. g. as a
 60

Geneva gear transmission operated from a suitable continuously driven shaft of the machine, as will be readily understood by those skilled in the art to which the present invention appertains.

Cooperative with each pick-up drum is a blade 5 stripping or transfer means, by which a blade is stripped from the pick-up drum and lowered into aligned relation with a receiver or pocket of the collecting and assembling conveyer, means co-operative with said stripping or transfer means 10 being provided for thrusting the stripped blade from the latter and thence into an awaiting receiver or pocket of the conveyer. To these ends the following mechanism is provided. Journaled in and between the standards 2 to extend back 15 of the pick-up drums 6 and beneath cam shaft 4 is a rock-shaft 95 to which is affixed an actuating lever arm 96. Fixed on the cam shaft 4 is a blade stripper actuating cam 97, the race of which is engaged by a roller stud 98 on the forked end 20 99 of a connecting rod 100, the free end of which is pivotally joined to said lever arm 96 (see Fig. 9). Also mounted to extend between said standards 2 above said rock-shaft 95 is a fulcrum shaft 101. Pivotally mounted on said 25 fulcrum shaft 101 are a plurality of stripper arms 102, the same being aligned with and extending respectively adjacent to the undersides of the respective pick-up drums 6. Secured to the forwardly extending portions of each stripper arm 30 102 to project forwardly therefrom in laterally spaced apart relation are a pair of stripper plates 103, the free end portions of which are horizontally bifurcated to provide outwardly open inwardly extending blade receiving slots 104. Secured to the outer faces of said stripper plates 35 103 are side or keeper plates 105 which border the outer sides of said blade receiving slots 104. The outer free end portions 106 of said side or keeper plates 105 project beyond the outer extremities 40 of said stripper plates 103, and are preferably somewhat laterally flared. The spaces between said stripper plates 103 are so dimensioned that the peripheral portions of the pick-up drums with which they cooperate may pass therebetween 45 so as to be straddled thereby when the stripper arms 102 are in normally upraised blade receiving positions. Also fulcrumed on said fulcrum shaft 101, in correspondence with each stripper arm 102, are rearwardly extending actuating levers 107 which extend beneath the rearwardly extending portions of said stripper arms 102. Extending loosely through the rearward end portion of each stripper arm 102 is an adjusting bolt 108 having a head 109 at its upper 55 end to engage said stripper arm, and having its lower end threaded into a cooperating actuating lever 107. A compression spring 110 is mounted around each bolt 108 between the stripper arm rear end and said actuating lever. Adjustably 60 mounted on each actuating lever 107 is a fulcrum block 111. Fixed on the rock shaft 95 for co-operation with each actuating lever 107 are rocker arms 112 which are respectively interconnected by links 113 to the fulcrum blocks 65 111 of the respective actuating levers 107 by which they are served.

In the operation of the blade stripping or transfer means, as revolution of the pick-up drums carries the suction cup gripped blades 70 beyond the detector mechanism and to positions at the undersides of said drums, the stripper arms 102, as the blades approach the same occupy their normal initial raised positions with their stripper plates 103 straddling the peripheries of 75

the drums, and with the blade receiving slots 104 at such level that the side marginal portions of the blade may enter into said receiving slots 104 (see Fig. 2 and full line representation in Fig. 9).
5 As the blades advance and fully enter said receiving slots 104, and between the keeper plates 105, which hold the same against lateral displacement relative to operative engagement thereof by the stripper plates 103, the ports 12 10 of the passages 11 serving the suction cups 8 carrying such blades, having ceased to communicate with the suction channels or ducts 16 of the pneumatic control valves, move into communication with the suction relief channels or ducts 17 of the latter, whereby communication with the atmosphere is established between said blade gripping suction cups 8 and the preceding suction cups of the drums, which have been previously relieved of the blades carried thereby, so 15 that the same and their passages and ports are open to the atmosphere, and consequently the inrush of air through said latter cups, passages and ports and thence through suction relief channel or duct 17 into the blade gripping cups and their passages and ports, immediately relieves or breaks the suction effect or grip of the latter upon the blades (see Fig. 8), and said blades are released so as to be held merely by the embrace of the gripper plates 103. By the 20 time these operations are accomplished, the actuating cam 97 is timed to impart, through the above described motion transmitting devices, downward swinging movements to said stripper arms 102, whereby the blades are carried downward and presented endwise to the blade receivers or pockets 94 of the collecting and assembling conveyer, which at such time has to rest for a dwell period of sufficiently long duration to admit of insertion or transfer of the 25 stripper arm carried blades thereinto (see dotted representation of the stripper arm arrangement shown in Fig. 9). The means provided for thrusting the blades out of the embrace of said stripper arms and into said conveyer receivers or pockets, comprises a suitably located and journaled rock-shaft 114 to which is affixed a rocker arm 115. Fixed on the cam shaft 4 is a blade pusher actuating cam 116, the race of which is engaged by a roller stud 117 carried by 30 a suitably pivoted actuating lever 118. Interconnected between said actuating lever 118 and said rocker arm 115 is an adjustable link 119. Fixed on said rock-shaft 114, for correspondence and cooperation with each stripper arm 102, are 35 oscillatable levers 120, equipped at their upper ends with up-standing push fingers 121 which respectively enter between the stripper plates 103 of said stripper arms 102, when the latter are lowered, being thus disposed behind the blades carried by said stripper arms (see Fig. 9). While the stripper arms 102 are lowered and movement of the collecting and assembling conveyer is arrested to present its receivers or pockets 94 for blade reception, the operation of the actuating cam 116 is timed to cause forward swinging movement of said levers 120, thereby causing the push fingers 121 to engage the adjacent blade ends so as to thrust the same outwardly from the embrace of the stripper arms 102 and thence into the awaiting conveyer receivers or pockets 34.

In the machine as disclosed by the accompanying drawings to illustrate the construction and novel mode of operation involved in the instant invention, five pick-up drums 6 are shown, each

of which simultaneously delivers, through the above described transfer mechanism, a single blade at a time respectively to five conveyer receivers or pockets aligned therewith. Upon each delivery of a blade into a pocket, and pending the delivery of a next succeeding blade, the collecting and assembling conveyer is advanced one step. As a consequence of this a given conveyer receiver or pocket 94, being initially aligned with the first pick-up drum on the left, receives one blade therefrom; whereupon said receiver or pocket 94 is advanced to align itself with the second pick-up drum and thereupon receives a second blade therefrom; thence to the third drum to receive a third blade; thence to the fourth drum to receive a fourth blade; and finally to the fifth drum to receive a fifth blade. In this manner as a given conveyer receiver or pocket 94 passes beyond the last drum, it carries with it an accumulation of five blades ready to be entered into an enclosing carton. In view of the fact, that the blades are thus successively piled up within the conveyer receivers or pockets 94 as the latter successively move from drum to drum, the downward oscillation or throw of the successive stripper arms 102 must be progressively diminished so as to hold the blades lowered thereby at proper levels to slide over and upon the blades previously deposited in the said receivers or pockets 94. Adjustments for such purpose may be made by positioning the fulcrum blocks 111 of the actuating levers 107 to increase or decrease the leverage exerted on the stripper arms to that calculated to arrest a given stripper arm in a desired selected lowered position. Slight adjustments of the stripper arms 102 relative to the means for actuating the same may be made for the purpose of precisely aligning the receiving slots 104 of the gripper plates 103 in the path of movement of blades advanced thereto by the pick-up drums. Such adjustments may be made by tightening down or relaxing the adjusting bolts 108, the compression springs 110 absorbing the movement, and being sufficiently strong to impart the motion of the actuating levers 107 to the stripper arms 102.

It will be understood that the actuating cams controlling the magazine and blade feeding operations, the blade testing or detecting operations, the blade stripping or transfer operation have a speed ratio to pick-up drum revolution equal to the number of suction cups carried by the drums.

It will also be understood that the ratio of movement of the pick-up drums relative to the step by step intermittent movement of the collecting and assembling conveyer may be suitably arranged according to the number of blades to be collected into a group for deposit in a carton. In the above description the arrangement is such that the movement of the pick-up drums is timed to deposit one blade during each period of conveyer receiver or pocket dwell. This may be altered however to vary the number of blades collected and assembled in group units. For example, the blades may be collected and assembled in groups of ten, by increasing the pick-up drum speed, and the speeds of associated mechanisms, relative to the conveyer speed, so that two blades will be deposited during each period of conveyer receiver or pocket dwell. Groups containing blades in multiples of other odd or even numbers may be collected and assembled by suitably arranging the drum speed relative to the conveyer speed, and then stopping off certain of the pick- 75

up drum suction cups. For example, groups of six blades may be collected by operating the pick-up drums as last above described, i. e. so as to deposit two blades during each period of conveyer receiver or pocket dwell, and thereupon blocking or stopping off every other suction cup of the first four drums, so that the first four drums will each deliver but a single blade during pocket dwell but the last or fifth drum, being effective as to all of its suction cups, will deliver two blades, thus accumulating six blades in each conveyer receiver or pocket.

As the blade collecting and assembling conveyer moves the blade filled receivers or pockets 94 thereof beyond the last drum, and prior to the positioning of said receivers or pockets ready for the ejection of the collected and assembled blades therefrom and delivery thereof into an awaiting carton, as will be subsequently described, a second blade testing or detector means is provided for engaging each group of blades so as to determine that the same contains the proper number of blades desired to be delivered to and enclosed within a carton. This second detector means comprises a standard 122 supported upon the platform or bed plate 1 adjacent to the inner side of said blade collecting and assembling conveyer. Vertically reciprocable upon said standard 122 is a carriage 123. Mounted on said carriage 123, subject to vertical adjustment relative thereto by means of an adjusting screw 124 which is rotatably journaled in an outwardly offset projection 125 with which said carriage 123 is provided, is a carrier block 126 into which said adjusting screw 124 is threaded. Said carrier block 126 is provided with vertically spaced and aligned forwardly offset bracket lugs 127 which overhang the top side of said blade collecting and assembling conveyer. Slidably mounted through said bracket lugs 127 is the stem 128 having a feeler finger means 129 at its lower free end. Suitably supported in a stationary position adjacent to said carriage 123 and its carrier block 126 is an electrical switch box 130 having an upwardly presented exteriorly projecting push button 131 for actuating the switch contained therein. Secured to the stem 128 of said feeler finger means 129, above the lower of the two bracket lugs 127, is a laterally extending arm 132, the free end portion of which overhangs said switch box 130. Adjustably affixed through the free end portion of said arm 132 is a depending push pin 133 which is aligned with and normally spaced above said switch box push button 131. A compression spring 134 is arranged around said stem 128 between said arm 132 and the upper of the two bracket lugs 127; said spring yieldably maintaining said feeler finger means 129 in normal downwardly projected position. Suitable means (not shown) are provided for producing a downward movement of said carriage 123 and the feeler finger means carried thereby during each period of dwell of the blade receivers or pockets 94 registered beneath said feeler finger means.

In the operation of the machine, said second detector or testing mechanism functions as follows:

As a conveyer receiver or pocket 94, containing a collected and assembled group of blades, passes beyond the last pick-up drum 6, and comes to rest during a period of conveyer dwell, the actuating mechanism for said second detector or testing means operates to slide downwardly the carriage 123 and the carrier block 126 mounted

thereon, whereby to press downwardly upon the group of blades contained in said receiver or pocket 94 the feeler finger means 129. If there is a full quota of five blades in said receiver or pocket 94, the downward movement of the feeler finger means will be arrested on contact therewith and will yield upwardly against the compression of the spring 134 as the carriage and carrier continues downward to completion of its operative down stroke. Such arrest of the feeler finger means stops the downward movement of the arm 132 and its push pin 133, the latter being thus also arrested before it can contact with and actuate the switch box push button 131. If, however, the receiver or pocket 94 contains less than five blades, the feeler finger means 129 will be permitted to move down far enough to contact and actuate the switch box push-button 131 so as to close an electrical circuit controlled thereby, thus energizing suitable means (not shown) whereby the machine is brought to a stop until the attendant fills up the quota of blades within the deficiently filled conveyer receiver or pocket 94 to the required number.

Mounted upon said platform or bed plate 1 in front of said blade collecting and assembling conveyer, is a carton carrying conveyer 135. This carton carrying conveyer runs parallel to the blade collecting and assembling conveyer, with the pockets 137 thereof, by which the empty cartons 137 are embraced, disposed in end to end alignment with the blade receivers or pockets 94 of said blade collecting and assembling conveyer, and, of course, said carton carrying conveyer is operated with the same intermittent movement and at the same speed as said blade collecting and assembling conveyer.

At a suitable point advanced beyond the pick-up drums and said second detector or testing mechanism, means are provided into operative alignment with which is arrested each blade containing receiver or pocket 94 of the blade collecting and assembling conveyer and a corresponding empty carton containing pocket 136 of said carton carrying conveyer 135, which means is timed, by suitable actuating mechanism, to thrust the group of blades out of the receiver or pocket 94 and into the awaiting empty carton 137 (see Fig. 1). This means comprises a suitable support 138 mounted upon said platform or base plate 1 in which is slidably arranged a reciprocable plunger element 139, the operative end 140 of which is aligned with the position of rest of the aforesaid conveyer pockets. Intermediate said arrested conveyer pockets is a suitably supported slideway 141 leading from the blade collecting and assembling pocket 94 to the pocket 136 of said carton carrying conveyer 135. While the conveyers and their said pockets are at rest, a suitably timed actuating lever 142, which is connected with said plunger element 139, slides the same forward, thereby carrying its operative end 140 into engagement with the group of blades in the blade collecting and assembling conveyer pocket so as to slide the same endwise out of said pocket, across said slideway 141, and into the empty carton 137 combined in the pocket of the carton carrying conveyer, and thereupon withdrawing back to normal initial position. In this way, the blade groups are successively entered in successive cartons, whereupon the carton carrying conveyer 135 carries on the filled cartons, to submit the same to suitable carton closing mechanism, after the operation of which the filled and closed cartons are discharged from the machine.

It will be understood that various changes may be made in the disclosed constructions, and many apparently widely different embodiments of this invention could be made without departing from 5 the scope thereof as defined in the hereinafter claims. It is therefore intended that all matter contained in the above description or shown in the accompanying drawings shall be interpreted as illustrative and not in a limiting sense.

10 We claim:—

1. In a machine of the kind described, a series of simultaneously revolved pick-up drums each having blade gripping suction cups spaced around the perimeters thereof, blade supporting means 15 adjacent to the rearward side of said drums, a corresponding series of pivoted blade magazines inclined toward said drums, means to produce timed vertical oscillation of the discharge ends of said magazines relative to said blade supporting means thereby to deliver and maintain groups of 20 blades upon said supporting means and segregated from the main supply of blades contained in said magazines, and detent means to hold said segregated blade groups normally out of contact 25 with said drums, and means to produce timed movement of said detent means to carry said blade groups toward said drums when suction cups of the latter are in blade receiving position, thereby to permit said cups to grip and remove the 30 outermost blades of said groups.

2. In a machine of the kind described, a series of simultaneously revolved pick-up drums each having blade gripping suction cups spaced around the perimeters thereof, blade supporting means 35 adjacent to the rearward side of said drums, a corresponding series of pivoted blade magazines inclined toward said drums, means to produce timed vertical oscillation of the discharge ends of said magazines relative to said blade supporting means 40 thereby to deliver and maintain groups of blades upon said supporting means and segregated from the main supply of blades contained in said magazines, and detent means to hold said segregated blade groups normally out of contact 45 with said drums, means to produce timed movement of said detent means to carry said blade groups toward said drums when suction cups of the latter are in blade receiving position, thereby to permit said cups to grip and remove the 50 outermost blades of said groups, and means to retain all but said cup gripped blades against displacement from said blade supporting means.

3. In a machine of the kind described, a series of simultaneously revolved pick-up drums each 55 having blade gripping suction cups spaced around their perimeters, blade supporting means adjacent to the rearward side of said drums, a corresponding series of pivoted blade magazines inclined toward said drums, means to produce timed 60 vertical oscillation of the discharge ends of said magazines relative to said blade supporting means to deliver and maintain segregated groups of blades upon the latter, timed means to move said blade groups toward said drums when suction 65 cups of the latter are in blade receiving position, thereby to permit said cups to grip and remove the outermost blades of said groups, a blade collecting and assembling conveyer to run beneath said drums, and means to strip blades from said 70 drums and deliver the same to said conveyer.

4. In a machine of the kind described, a series of simultaneously revolved pick-up drums each having blade gripping suction cups spaced around their perimeters, blade supporting means adjacent to the rearward side of said drums, a corre- 75

sponding series of pivoted blade magazines inclined toward said drums, means to produce timed vertical oscillation of the discharge ends of said magazines relative to said blade supporting means to deliver and maintain segregated groups of 5 blades upon the latter, timed means to move said blade groups toward said drums when suction cups of the latter are in blade receiving position, thereby to permit said cups to grip and remove the outermost blades of said groups, a blade collecting and assembling conveyer to run beneath said drums, means to strip blades from said drums and deliver the same to said conveyer, a conveyer parallel to said blade collecting and assembling conveyer adapted to carry and position enclosures 10 for the reception of blades from the latter, and means for transferring the blades from the blade conveyer into said enclosures.

5. In a machine of the kind described, a series of simultaneously revolved pick-up drums each 20 having blade gripping suction cups spaced around their perimeters, each drum having suction ducts leading to said suction cups, a stationary pneumatic valve means for each drum having suction control means served by suction inducing means 25 into and out of communication with which said suction ducts move and suction relief means into and out of communication with which said suction ducts likewise move, means for supplying blades to each suction cup of each drum as said 30 cup moves into communication with the suction control means serving its drum, an intermittently actuated blade collecting and assembling conveyer having pockets to successively receive blades from each drum to assemble in said pockets blade 35 groups of predetermined number, means for stripping the blades from each suction cup of each drum as said cup moves into communication with the suction relief means serving its drum, and means for depositing the thus stripped 40 blades in said conveyer pockets.

6. In a machine of the kind described, a series of simultaneously revolved pick-up drums each having blade gripping suction cups spaced around their perimeters, each drum having suction ducts 45 leading to said suction cups, a stationary pneumatic valve means for each drum having suction control means served by suction inducing means into and out of communication with which said suction ducts move and suction relief means into 50 and out of communication with which said suction ducts likewise move, means for supplying blades to each suction cup of each drum as said cup moves into communication with the suction control means serving its drum, an intermittently 55 actuated blade collecting and assembling conveyer having pockets to successively receive blades from each drum to assemble in said pockets blade groups of predetermined number, means for stripping the blades from each suction cup to 60 each drum as said cup moves into communication with the suction relief means, serving its drum, and means for depositing the thus stripped blades in said conveyer pockets, a conveyer parallel to 65 and synchronously actuated with said blade collecting and assembling conveyer adapted to carry and position enclosures for the reception of said blade groups, and means for transferring said blade groups from the blade conveyer into said 70 enclosures.

7. In a machine of the kind described, a series of simultaneously revolved pick-up drums each having blade gripping suction cups spaced around their perimeters, each drum having suction ducts leading to said suction cups, a stationary pneu- 75

of simultaneously revolved pick-up drums each having blade gripping suction cups spaced around their perimeters, each drum having suction ducts leading to said cups, a stationary pneumatic valve means for each drum having suction control means served by suction inducing means into and out of communication with which said suction ducts move and suction relief means into and out of communication with which said suction ducts likewise move, a blade supporting means adjacent to the rearward side of said drums, a corresponding series of pivoted blade magazines inclined toward said drums, means to produce timed vertical oscillation of the discharge ends of said magazines relative to said blade supporting means to deliver and maintain segregated groups of blades upon the latter, and detent means to hold said blade groups normally out of contact with said drums, means to produce timed movement of said detent means to engage blades from said groups with presented suction cups of said drums, means to retain all but said cup gripped blades against displacement from said blade supporting means, an intermittently actuated blade collecting and assembling conveyer running across and beneath said drums, and means to strip blades from said drum and deliver the same to said conveyer, said conveyer being adapted to accumulate blades successively from each drum to produce unit groups thereof of predetermined number.

13. In a machine of the kind described, a series of simultaneously revolved pick-up drums each having blade gripping suction cups spaced around their perimeters, each drum having suction ducts leading to said cups, a stationary pneumatic valve means for each drum having suction control means served by suction inducing means into and out of communication with which said suction ducts move and suction relief means into and out of communication with which said suction ducts likewise move, a blade supporting means adjacent to the rearward side of said drums, a corresponding series of pivoted blade magazines inclined toward said drums, means to produce timed vertical oscillation of the discharge ends of said magazines relative to said blade supporting means to deliver and maintain segregated groups of blades upon the latter, and detent means to hold said blade groups normally out of contact with said drums, means to produce timed movement of said detent means to engage blades from said groups with presented suction cups of said drums, means to retain all but said cup gripped blades against displacement from said blade supporting means, an intermittently actuated blade collecting and assembling conveyer running across and beneath said drums, and means to strip blades from said drum and deliver the same to said conveyer, said conveyer being adapted to accumulate blades successively from each drum to produce unit groups thereof of predetermined number, a carton conveyer parallel to and synchronously actuated with said blade conveyer, and means for transferring said blade groups from the blade conveyer into the cartons carried by said carton conveyer.

14. In a machine of the kind described as defined in claim 13, means cooperative with said drums effective to cause stopping of the machine if any drum suction cup fails to carry a blade.

15. In a machine of the kind described as defined in claim 13, means cooperative with said blade conveyer effective to cause stopping of the

machine if any blade group carried by said conveyer lacks a proper number of blades.

16. In a machine of the kind described as defined in claim 13, means cooperative with said drums effective to cause stopping of the machine if any drum suction cup fails to carry a blade, and additional means cooperative with the blade conveyer also effective to cause stopping of the machine if any blade group carried by said conveyer lacks a proper number of blades. 10

17. In a machine of the kind described, a revolved pick-up drum having blade gripping means spaced around the perimeter thereof adapted to successively take up blades from a source of supply thereof, and means to successively strip said blades from the drum, said latter means comprising a stripper arm oscillatable toward and from said drum, said stripper arm having laterally spaced stripper plates to straddle said drum, said stripper plates having outwardly open longitudinal slots into which the blades are carried by said drum, and means to hold the entered blade against lateral displacement relative to stripper plates. 15

18. In a machine of the kind described, a series of simultaneously revolved pick-up drums having blade gripping means spaced around their perimeters and adapted to successively take up blades from a source of supply thereof, an intermittently actuated blade collecting and assembling conveyer having blade receiving pockets running across and beneath said drums, said conveyer being adapted to accumulate blades successively from each drum to produce unit groups thereof of predetermined number, pivoted stripper arms oscillatable between said drums and conveyer, said stripper arms having laterally spaced slotted stripper plates to straddle said drums and into the slots of which blades are carried by said drum, means to hold said blades against lateral displacement relative to said stripper plates, and means to transfer blades from the stripper plates into said conveyer pockets when the stripper arms are moved from said drums toward said conveyer. 40 45

19. In a machine of the kind described, a series of simultaneously revolved pick-up drums having blade gripping means spaced around their perimeters and adapted to successively take up blades from a source of supply thereof, an intermittently actuated blade collecting and assembling conveyer having blade receiving pockets running across and beneath said drums, said conveyer being adapted to accumulate blades successively from each drum to produce unit groups thereof of predetermined number, pivoted stripper arms oscillatable between said drums and conveyer, said stripper arms having laterally spaced slotted stripper plates to straddle said drums and into the slots of which blades are carried by said drum, means to hold said blades against lateral displacement relative to said stripper plates, means to transfer blades from the stripper plates into said conveyer pockets when the stripper arms are moved from said drum toward said conveyer, means for producing oscillations of said stripper arms timed to the movements of said drum blade gripping means relative thereto, and means for individually regulating the oscillation amplitude of said stripper arms. 50 55 60 65

20. In a machine of the kind described, a revolved pick-up drum having article gripping means spaced around the perimeter thereof, article supporting means adjacent to the drum per- 70 75

5 imeter, a pivoted article magazine inclined toward said supporting means, means to produce timed oscillation of the discharge end of said magazine relative to said supporting means thereby to deliver upon the latter a group of articles segregated from the main supply thereof contained in the magazine, a detent means to hold the segregated article group normally out of contact with said drum, means to produce timed movement of 10 said detent means to carry the article group toward the drum and the outermost article thereof into engagement with an article gripping means of the drum, and means to retain all but the gripped article against displacement from said 15 supporting means.

21. In a machine of the kind described, a revolved pick-up drum having article gripping means spaced around the perimeter thereof, article supporting means adjacent to the drum perimeter, a pivoted article magazine inclined toward said supporting means, means to produce timed oscillation of the discharge end of said magazine relative to said supporting means thereby to deliver upon the latter a group of articles segregated from the main supply thereof contained in the magazine, a detent means to hold the segregated article group normally out of contact with said drum, means to produce timed movement of 25 said detent means to carry the article group toward the drum and the outermost article thereof into engagement with an article gripping means of the drum, means to retain all but the gripped article against displacement from said supporting means, and means to produce timed movement of 30 said last mentioned means toward the drum after movement of the gripped article is initiated thereby to engage and hold said gripped article against displacement from the gripping means, and until said gripped article is entirely 35 freed from contact with said segregated group thereof.

22. In a machine of the kind described, a series of laterally spaced drums simultaneously rotatable about a common axis, said drums having 40 blade pick-up and carrying means spaced around their perimeters, said pick-up and carrying means

of each drum being adapted to successively take up blades from sources of supply thereof respectively provided for each drum, an intermittently actuated blade collecting and assembling conveyer running beneath and transversely of said drums, said conveyer having blade receiving pockets successively spaced thereon in correspondence to the spacing of said drums, said conveyer being adapted to accumulate blades successively from the drums so as to collect in the pockets thereof unit groups containing a desired predetermined number of blades, oscillatable means intermediate said drums and conveyer adapted to release blades from the drums, and a second oscillatable means to transfer blades from the latter means 15 to the conveyer pockets.

23. In a machine of the kind described, a series of laterally spaced drums simultaneously rotatable about a common axis, said drums having blade pick-up and carrying means spaced around 20 their perimeters, said pick-up and carrying means of each drum being adapted to successively take up blades from sources of supply thereof respectively provided for each drum, an intermittently actuated blade collecting and assembling conveyer running beneath and transversely of said drums, said conveyer having blade receiving pockets successively spaced thereon in correspondence to the spacing of said drums, said conveyer being adapted to accumulate blades successively from 25 the drums so as to collect in the pockets thereof unit groups containing a desired predetermined number of blades, oscillatable means intermediate said drums and conveyer to release blades from the drums, a second oscillatable means to transfer 30 blades from the latter means to the conveyer pockets, a second conveyer means moving synchronously with and parallel to said collecting conveyer, said second conveyer having blade carton supporting pockets correspondingly spaced and 35 aligned with the collecting conveyer pockets and timed means to transfer blade groups from said collecting conveyer pockets into said blade cartons.
